BUNGALOW

Frank F. Townsend, Camden, N. J.

Application July 21, 1936, Serial No. 91,675

4 Claims.

This invention relates to dwellings of the bungalow type. Special objects of the invention are to provide desirable ventilation, lighting, heating or cooling and air conditioning in a building of this type and a readily assembled relatively inexpensive form of construction, which will be rugged and strong and provide maximum useful space for living purposes.

These and other desirable objects are attained by the novel features of construction, combinations and relations of parts hereinafter described, broadly covered in the claims and illustrated by way of disclosure in the accompanying drawings.

The drawings show practical preferred embodiments of the invention, but it will be appreciated that the structure may be modified and changed in various ways all within the true intent and broad scope of the invention.

Fig. 1 is a partial plan view of the structure with the roof cover removed to show interior details.

Fig. 2 is a horizontal plan view of the wall structure, as with the roof and ceiling removed.

Fig. 3 is a broken and part vertical sectional view of the building.

Fig. 4 is an interior perspective illustration of the ceiling structure.

Fig. 5 is a longitudinal sectional view illustrating ventilating and air conditioning features and omitting other details.

Fig. 6 is a broken sectional detail of a built-in form of air conditioning unit.

Fig. 7 is a broken part sectional end elevation of the building.

Fig. 8 is an enlarged and broken vertical sectional view on substantially the line 8-8 of Fig. 7 illustrating details of one of the dormers which may be provided over the ends of the trunks which open through the roof.

Fig. 9 is a horizontal broken sectional detail of the corner construction.

Fig. 10 is a broken perspective view of one of the corner reinforcing and tie members.

A special feature of the bungalow illustrated is that it can be built without studding and that the roof and ceiling structure can be sustained entirely by the siding. The siding represented at 50 11, is shown as made up of vertical lapped boards resting on suitable foundation 12, and carrying rails or supports 13, for the rafters 14.

The sills are shown as composed of inner joists 15, which may be notched at 16, for the floor beams 17, Figs. 7 and 8, attached to intermediate

edgeset boards 18, which extend up above the flooring 19, sufficient to form the floor molding 20 and the outer edgeset boards 21, which extend up beyond the molding board sufficiently to form the mop board 22. These three sill and trim 5 forming members may be nailed, bolted or otherwise suitably fastened together and the vertical siding may be nailed or otherwise fastened to the outermost of these.

In the illustration, the vertical side walls extend only to approximately the top of the window level and the additional desired height is given the rooms by locating the ceiling 23, up in the rafter space and by connecting this elevated ceiling with the side walls by the inclined ceiling 10 flanges 24.

Where the house is more than two rooms deep, as in the illustration, this drop-ceiling effect is carried out between adjoining rooms by the similarly inclined drop flanges 25, meeting at the 15 partition walls 26, between the rooms.

These meeting inclined ceiling walls 25 provide at the top of the ceiling structure longitudinally and transversely extending substantially V-shaped troughs 27, available for 20 ventilating and like purposes.

Where four rooms adjoin, diagonally set cubicles 28, are provided and these may be of a height corresponding to the height of the siding and closed at the top by a flat ceiling 29, at that 30 level and providing a flat cross-over for the intersecting V-shaped ducts at that point.

These cubicles or small corner rooms, which in effect are taken out of the corners of four adjoining rooms are useful for toilet or heating, 35 cooling or air conditioning or for pantry, storage or wardrobe purposes. In Fig. 2, one of the intermediate corner rooms or spaces is shown as containing the accessories 29a, for toilet purposes and the other is shown as having an air 40 conditioning plant 30, arranged therein. These may have one or more doors opening from one or more of the four surrounding rooms. Necessary wiring and piping also may conveniently be located in these intermediate and closed 45 spaces between the adjoining rooms.

To utilize the V-troughs in the ceiling as definite air trunks, they may be closed over at the top as indicated at 31, Figs. 3 and 5, and opened at the ends to the outside air as indicated at 32. 50 These air inlet and exit ends may be protected from the weather as by suitably shuttered and screened dormers 33. Also, or in place of the circulation described, the connecting longitudinal and transverse V-ducts may be 55 connected by

vertical conduits 34, Figs. 3 and 7, with an inverted V-shaped trunk 35, in the peak of the rafters protected at opposite ends of the building as by the suitably screened dormers 36. By suitable checks and dampers, circulation through the ventilating ducts described may be governed according to the direction of wind flow to accomplish desired ventilating, heating and cooling effects. By suitably controlled inlets to and from the various rooms, such circulation may be utilized to suit particular requirements of different rooms. Fig. 8 shows one form of such controllers, in which room openings 31, in the inclined drop flanges may be governed by hinged valves or gates 38, which can be shifted and secured in various positions by securing handles 39. In this particular illustration, the closure member 38 is in the nature of a window having glass panes 40, letting light into two adjoining rooms and the opening of this window provides communication between the ceiling passageway 27, and these two rooms at opposite sides of the same.

Further ventilation and air circulation is effected in the illustration by the provision of boxes 41, Figs. 7 and 8, over the windows and by the provision of double sliding sash 42, spaced from and in addition to the regular inner sliding sash 43. The upper outer sash is shown as carrying a plate 44, which when this sash is entirely raised will close an opening 45, in the upper end of the box communicating with a wall opening 46, over the top of the window and the lower outer sash is shown as carrying a plate 47, which when this sash is down will close an opening 48, communicating through the box with a wall opening 49, below the window and in back of the heating radiator 50. By more or less opening the outer sliding sash as indicated, leaving the inner sash closed, circulation may be created into and from the room.

A heating or cooling or air conditioning plant or combination of any two or all three of these may be located at 30, Figs. 2 and 5, in any one or all of the intermediate chambers 28. Such a combination unit is indicated in Fig. 6, involving an air conditioner 51, through which water is passed by piping 52, and which may be heated or cooled as conditions require by the instrumentalities indicated at 53. This unit is shown as having a casing 54, divided by partitions into an upper compartment 55, taking air from the attic duct 35, and discharging through an injector 56, into an adjoining compartment 57, taking air from the various rooms, the conditioned air passing from the lower compartment 58, out through ducts 59, to the several rooms.

At the corners of the building, the members of the built-up sill may be connected and reinforced by the joining strip 60, shown in Figs. 9 and 10, as having reversely bent tabs 61, 62, at its upper and lower edges nailed or otherwise secured over the edges of the adjoining beam members. Only one or both sets of these tabs or lugs may be used, depending on the special conditions. In the particular case illustrated, the lugs 62, are bent in reversely extending relation at the lower edge of the joining strip and secured beneath the beams 15, 18, 21, whereas at the top, one set of lugs 61, are bent in and secured over the top of the inner sill beam 15, and other of these top lugs are left standing up

straight and are secured to the inner face of the intermediate beam 18, or on the fastener strip 60 between the intermediate beam 18, and inner face of beam 21, all the top lugs may be left standing up straight and only those 62, at the bottom be utilized. These joining strips with the securing tabs may be used in various other ways for fastening beams and other building elements together.

The intermediate chambers between the rooms 10 may vary in size according to their use. In addition to heating and toilet equipment, these chambers may be used for kitchen equipment and as vertical ducts for pipes, wiring, lightning rods and other elements.

In addition to or in place of manually operated dampers and valves for controlling circulation in the ventilating ducts, automatic valves may be placed, for instance, in the gable and ceiling ducts for controlling entrance and exit of air in accordance with the direction of wind flow.

The windows, particularly the outer windows, such as indicated at 42 (Fig. 8) may be mounted to swing outward or inward and be hinged either at the top or bottom. The siding 11 may be extended up to the roof or sheathing 63. Similarly, the partitions 26 may be extended up through the troughs 27 to the joists or roof beams. Radiators, such as shown at 64, may be located either within or outside the air-conditioning chambers, as indicated in Figs. 5 and 6.

What is claimed is:

1. In a building of the character disclosed, siding, rafters supported by said siding and a ceiling having an inclined drop flange extending partly up said rafters and other drop flanges meeting in the form of V-shaped ventilating troughs in the ceiling and room defining partitions at the juncture of said meeting ceiling flanges.

2. In a building of the character disclosed, siding, rafters supported by said siding and a ceiling having an inclined drop flange extending partly up said rafters and other drop flanges meeting in the form of V-shaped ventilating troughs in the ceiling, room defining partitions at the juncture of said meeting ceiling flanges and intermediate chambers at the juncture of different rooms and formed by walls in the adjoining corners of such rooms, said intermediate chambers having ceilings at the lower level of said drop flanges and forming connecting portions of the ventilating troughs.

3. A building having a peaked roof, an inverted V-shaped ventilating trunk under the peak of said roof, partitions dividing the interior of the building into rooms, ceilings for said rooms having inclined drop flanges forming V-shaped troughs, said troughs being closed over at the top and conduit connections from said peak trunk to said covered ceiling troughs.

4. A building having a peaked roof, an inverted V-shaped ventilating trunk under the peak of said roof, partitions dividing the interior of the building into rooms, ceilings for said rooms having inclined drop flanges forming V-shaped troughs, said troughs being closed over at the top and conduit connections from said peak trunk to said covered ceiling troughs and means for establishing communication between said peak trunk and the outside air.
